UNITED STATES PATENT OFFICE

167,824

HOSIERY DISPLAY RACK OR SIMILAR ARTICLE

Grace Jones Colombo, New York, N. Y., assignor to Hanes Hosiery, Inc., New York, N. Y., a corporation of New York

Application October 20, 1951, Serial No. 17,052

Term of patent 14 years

(Cl. D80--9)

To all whom it may concern:

Be it known that I, Grace Jones Colombo, a citizen of the United States, residing at 307 East 44th Street, New York city, in the county of New York, State of New York, have invented a new, original, and ornamental Design for a Hosiery Display Rack or Similar Article, of which the following is a specification, reference being had to the accompanying drawing, forming part thereof.

Fig. 1 is an isometric perspective view of a hosiery display rack, showing my new design.

Fig. 2 is a cross-sectional view showing the contour of the arm portion of a hosiery display rack of my new design.

I claim:

The ornamental design for a hosiery display rack or similar article, as shown.

GRACE JONES COLOMBO.
